UNITED STATES PATENT OFFICE

144,692

DESIGN FOR A COMBINED CASE AND CRIBBAGE BOARD

Virgil David Canfield, Vashon, Wash.

Application September 22, 1945, Serial No. 122,260

Term of patent 14 years

(Cl. D34—5)

To all whom it may concern:

Be it known that I, Virgil David Canfield, a citizen of the United States and a resident of Vashon, in the county of King and State of Washington, have invented a new, original, and ornamental Design for a Combined Case and Cribbage Board, of which the following is a specification, reference being had to the accompanying drawing, forming a part thereof.

In said drawing:

Figure 1 is a top plan view of a combined case and cribbage board showing my new design, the

underside thereof having substantially the same appearance as the top shown.

Figure 2 is a side elevational view thereof; and Figure 3 is an end elevational view thereof.

The dominant feature of the invention is the spiral development of the track along which the pegs are moved in playing the game of cribbage.

I claim:

The ornamental design for a combined case and cribbage board, as shown and described.

VIRGIL DAVID CANFIELD.
